ARTICLE ASSEMBLING APPARATUS

George Stuhlfauth, Chicago, Ill., assignor to
Western Electric Company, Incorporated, New
York, N. Y., a corporation of New York

Application July 8, 1944, Serial No. 544,088

11 Claims. (Cl. 29—33)

This invention relates to article assembling apparatus and more particularly to an apparatus for assembling insulating elements in receiver units.

In the manufacture of some communications apparatus, an acoustic receiver element or unit is formed as an individual part and comprises a magnet assembly having coils thereon, the cores of which extend beyond the coils through an insulating member and are adapted to magnetically attract a receiver diaphragm which rests on the upper surface of the unit and on the core members of the coils. It is essential, in this apparatus, to have a slight air gap between the insulating member and the diaphragm to be placed thereover to permit vibration of the diaphragm in the reception of sound through the receiver apparatus.

It is an object of the present invention to provide a simple and efficient apparatus for rapidly assembling parts of acoustic apparatus.

In accordance with one embodiment of the invention, a receiver unit having a core member therein, on which coils are wound, is placed on a suitable fixture for supporting it in position to have an insulator attached to it. The insulator, prior to being placed on the coils and held in position in the unit, has a small amount of thermoplastic adhesive material applied to it on the side thereof to engage the coils, the insulator being suitably apertured to permit the extending core members to pass through it. After the unit is placed on the fixture, a manually operable and magnetically releasable lever is operated to move a heating element into engagement with the exposed surface of the insulator and, simultaneously, to close a circuit to a suitable timing device. The timing device is operative, after a predetermined interval, to direct fluid under pressure to one end of a piston carrying a crimping tool which surrounds the heating element and is reciprocable with respect thereto. The piston will drive the crimping tool down to crimp an edge of the capsule over the insulator, thus to fix it securely in place.

A complete understanding of the invention may be had by reference to the following detailed description when considered in conjunction with the accompanying drawings, wherein

Fig. 1 is a side elevational view, partly in section, of an apparatus embodying the features of the invention;

Fig. 2 is a vertical sectional view taken substantially along the line 2—2 of Fig. 1 in the direction of the arrows and showing details of

construction of the crimping tool and heating element on a slightly enlarged scale;

Fig. 3 is a diagrammatic view showing the hydraulic and electrical circuits of the apparatus;

Fig. 4 is an enlarged fragmentary elevational view, partly in section, showing details of construction of the lower end of the crimping and heating tools with the heating tool in its operated position and the crimping tool in its unoperated position;

Fig. 5 is a view similar to Fig. 4, but showing the crimping tool in its operated position; and

Fig. 6 is an exploded view in perspective of a receiver unit and insulator prior to their assembly.

Referring to the drawings, wherein like reference characters designate the same parts throughout the several views, particular reference first being had to Fig. 1, it will be seen that the apparatus includes a base 11, which may be mounted upon a suitable table or bench to make the apparatus easily accessible to an operator. At the rear of base 11, that is, at the right hand side, as viewed in Fig. 1, a back plate 12 is attached to the base 11 and extends upwardly to support various parts of the apparatus, being suitably fixed at its upper end to a top plate 13. The base 11 has a fixture supporting block 14 suitably attached to it to receive a fixture 15 which is, in turn, adapted to receive a receiver capsule or unit 16 and to position it in exact alignment with a reciprocable heating unit 17, which comprises, as shown most clearly in Figs. 2 and 4, a heater element 18 set into a copper heat transfer member 19, which is shaped at its lower end to conform to the shape of an insulator 20. The copper insert 19 is milled out, as shown at 21, to receive the heater element 18 and has a pair of clearance pockets 22—22 formed in it into which the pole pieces 23 of a magnet assembly 24 may extend when the heating unit 17 is in engagement with the insulator 20, thus to apply heat to the insulator without overheating the pole pieces 23.

The heating unit 17 is suitably fixed in the end 45 of an irregularly shaped sleeve 25, which is slidably mounted in the central bore 26 of a crimping tool 27 and in a bearing ring 28. Extending outwardly from the sides of the bearing ring 28 are a pair of trunnions 29—29 having reduced inner ends 30—30 extending into slots 31—31 formed in the sleeve 25. The upper end of the sleeve 25 is threaded to receive a stop nut 32, one side of which is split so that it may be locked in place on the sleeve 25 by means of a locking screw 33. Interposed between the bearing ring 28 and

a shoulder 34 formed on the sleeve 25 is a compression spring 35, which normally urges the sleeve 25 to hold the stop nut 32 against the upper surface of the ring 28, but which may be compressed slightly when the lower end of the copper heat transfer member 19 engages the insulator 20.

The bearing ring 28 is slidably mounted in a tool actuating tube 45, into the lower end of which the crimping tool 27 is threaded. The upper end of the tool actuating tube is threaded to receive a connector block 46 suitably attached to the lower end of a piston rod 47 by means of a shouldered ring 48 having an annular shoulder 49 adapted to engage a cooperating shoulder 50 on a connector bolt 51 threaded into the piston 47 and locked in place thereon by a lock nut 52. The tool actuating tube 45 is slidable in a bore 53 formed in a support block 54. The support block 54 has a base portion 55, as shown most clearly in Figs. 1 and 2, which is mounted in spaced relation to the base 11 by means of spacers 56-56 and bolts 57-57, the bolts 57 having their heads nested in suitable sockets in the base 11 and being threaded into standards 58-58, which cooperate with the support block 54 in supporting a cylinder 59 adjacent to the top plate 13.

The trunnions 29-29 extend through aligned slots 60-60 and 61-61 formed in the tool actuating tube 45, and support block 54. At their outer ends, the trunnions 29 are fixed to links 62-62, which are, in turn, pivotally connected to arms 63-63 of a bifurcated manually operable lever 64, the bifurcated portions of which extend on opposite sides of the support block 54 and are pivotally connected to the support block 54 by means of pivot pins 65-65 threaded into the support block 54.

From the foregoing, it is believed to be apparent that when the manually operable lever 64 is moved from its full line position, as shown in Fig. 1, to the position shown by the dot and dash lines, the links 62-62 will be moved to a position where they extend vertically, a stop pin 66 being mounted on the support block 54 to prevent the lever 64 from moving beyond the position shown in dot and dash lines. When the lever 64 is rocked to the position shown in dot and dash lines, the bearing ring 28 will be moved to the position shown in Fig. 2 and will, through the action of spring 5, push the sleeve 25 to the position shown in Fig. 2. The right end of the lever 64, as shown in Fig. 1, has a latching extension 75 formed thereon and adapted to engage a latch 76, which is normally urged to rock clockwise (Fig. 1) by a spring 77, which urges the latch 76 into engagement with a stop pin 78 mounted on the support block 54. The latch 76 is pivoted upon a pivot pin 79 and may be rocked counterclockwise upon energization of a solenoid 80, the movable core 81 of which is connected to the latch 76 by a link 82. Pivotally connected to the right hand arm 63 (Fig. 2) of the lever 64 is a plunger 83, which, as shown most clearly in Fig. 1, has a reduced portion 84 slidably mounted in a pivoted bearing block 85, which is pivotally mounted on a bracket 86, in turn supported on the support block 54. Interposed between the pivoted bearing block 85 and the larger portion of the plunger 83 is a compression spring 87, which normally tends to hold the plunger 83 in the position shown in Fig. 1 and, consequently, to hold the lever 64 in the position shown in full lines. Upon manual actuation of the lever 64,

5 the plunger 83 will carry an adjustable actuator screw 88 into engagement with the operating plunger 89 of an electrical switch 90. The switch 90, as shown diagrammatically in Fig. 3, is provided with contacts 91, which will be closed when the actuator screw 88 engages the operating plunger 89 of the switch 90. These contacts are normally open and control a timer 92 of a suitable type mounted on the back plate 12 of the apparatus.

10 The electrical circuit of the apparatus includes, in addition to the timer 92, a pair of switches 101 and 102, which serve to control the operation of the solenoid 80, and a reversing valve mechanism 103, which includes a pair of solenoid coils 104 and 105 operable upon alternate energization to attract core members 106 and 107. The core members 106 and 107, upon actuation, will rock a valve control lever 108 to shift a valve 109 from one of its operative positions to another of its operative positions, depending upon which of the two core members is actuated. The valve 109 serves to control the flow of fluid under pressure from an inlet pipe 110 to either a pipe 111 or a pipe 112 leading to the upper end and lower end, respectively, of the cylinder 59. The valve 109, upon operation, will serve to connect the inlet pipe 110 to either the pipe 111 or 112 to simultaneously connect the opposite one of the pipes 111 or 112 to an outlet pipe 113.

15 From the foregoing, it is believed to be apparent that when either the solenoid coil 104 or the solenoid coil 105 is energized, the valve 109 will be shifted to direct fluid under pressure to either the upper or the lower end of the cylinder end 59 and the fluid in the opposite end of the cylinder will be directed out through the pipe 113. It should be noted at this time that, upon operation of the valve 109, the valve will remain in the position to which it is shifted, thus to continue to supply fluid in a selected direction although the solenoid which had last been energized may be deenergized and that the valve will continue to direct the fluid in the selected direction 20 until the opposite solenoid coil is energized.

25 From the foregoing, it is believed to be apparent that when either the solenoid coil 104 or the solenoid coil 105 is energized, the valve 109 will be shifted to direct fluid under pressure to either the upper or the lower end of the cylinder end 59 and the fluid in the opposite end of the cylinder will be directed out through the pipe 113. It should be noted at this time that, upon operation of the valve 109, the valve will remain in the position to which it is shifted, thus to continue to supply fluid in a selected direction although the solenoid which had last been energized may be deenergized and that the valve will continue to direct the fluid in the selected direction 20 until the opposite solenoid coil is energized.

30 The switches 101 and 102, briefly described hereinbefore, are provided with normally open contacts 114 and 115, which are adapted to be controlled by levers 116 and 117. The levers 116 and 117, as may be seen most clearly in Fig. 1, are pivotally mounted on suitable brackets extending from the support block 54 and carry adjustable actuator members 118 and 119 in alignment with actuating plungers 120 and 121 of the switches 101 and 102, respectively. The left ends of the levers 116 and 117 are in alignment with the lower end of the tool actuating tube 45 and the upper surface of the shouldered ring 48, respectively, whereby, when the piston rod and tool actuating tube are in their lowermost position, the lever 116 will effect the closure of contacts 114 and when the piston rod 47 and tool actuating tube 45 are in their uppermost position, lever 117 will effect the closure of switch 102.

35 When the apparatus is operated to clamp an insulator in a receiver unit, the tool actuating tube will, of course, be moved downwardly and when it is moved downwardly, it will carry the lower end of the crimping tool 27 down into engagement with an upstanding annular rib 130 formed on an inwardly extending annular shoulder 131 of the base of the receiver unit 16, as illustrated most clearly in Figs. 4 and 5. Therefore, the 40 lower end of the crimping tool is provided with

a crimping portion 132, which will engage the rib 130 and bend it from the position shown in Fig. 4 to the position shown in Fig. 5. It should be noted at this time that a series of vertically extending holes 133 are formed in the crimping tool 141 in order to prevent it from overheating by permitting the circulation of air through the body of the tool.

A more complete understanding of the invention may be had by reference to the following brief description of the operation of the apparatus. In assembling the washer 20 on the receiver unit 16, an operator may first apply a small amount of adhesive material to the face of the insulator 20, which is to engage the coils of the receiver unit. This adhesive material is designated 134 in Figs. 4 and 5. As soon as the operator has applied some adhesive material to the insulator 20, the insulator may be placed on the receiver unit with the pole pieces 23 of the insulator unit extending through apertures in the insulator. Thereupon, the receiver unit may be placed upon the fixture 15 and the fixture may then be set into the fixture supporting block 14 and properly aligned to position the pole pieces 23 directly beneath the pockets 22 formed in the heat transfer member 19. With the receiver unit in place beneath the heat transfer member 19, the manually operable lever 64 may be moved from its full line position, as shown in Fig. 1, to its dot and dash line position, as shown in Figs. 1 and 3, thus to move the links 62-62 to a vertical position and, accordingly, push the heat transfer member 19 down onto the top of the insulator 20. The heat transfer member 19 will be heated by the heater element 18, which is supplied with current from a 110 volt A. C. source 135 through a rheostat 136 and will immediately start to heat the insulator 20 and thus render the adhesive sufficiently plastic that the adhesive may be compressed somewhat and the insulator 20 may be forced down onto the annular shoulder 131. As the manually operable lever 64 reaches its operated position, it will engage the latch 76 and will be latched in its operated position. The lever 64 will also actuate the plunger 83 and effect the closure of switch 90. One side of the contacts 91 of the switch 90 is connected to one end of a source of 110 volt A. C. 137 and, upon closure of the contacts 91, a circuit will be completed through the contacts 91, contacts 115 now closed because the piston rod 47 is in its uppermost position (opposite to that shown in Fig. 3), and back to the timer 92, thus to initiate a timing cycle of the timer 92. The timer 92 may, as pointed out hereinbefore, be of any suitable type and in the preferred embodiment of the invention is one which may be adjusted over a predetermined range, which will include a range of ten seconds. As soon as the circuit to the timer 92 is completed, the timer will start to operate and, after ten seconds, will complete a circuit to energize solenoid coil 104 to move the lever 108 to the position shown in Fig. 3. When the lever 108 is moved to the position shown in Fig. 3, the valve 109 will direct fluid under pressure from the inlet pipe 110 through pipe 111 to the upper end of the cylinder 59, thus to cause piston rod 47 to move downwardly. As the piston rod 47 moves downwardly, it will carry the crimping tool 27 with it, thus to move the tool 27 from the position shown in Fig. 4 to the position shown in Fig. 5 and crimp the rib 130 over the top surface of the insulator 20. As shown in the circuit di-

agram, the solenoid coil 104 is energized and the piston rod 47 has almost reached the bottom of its travel, where the tool actuating tube 45 will move its lower end into engagement with the lever 116 and close the contacts 114. Closure of the contacts 114 will complete a circuit from one side of the current source 137 through the solenoid 80 and solenoid coil 105 in parallel and back to the other side of the current source 137. This will energize the solenoid 80 and release the latch 76, thus permitting the plunger 83 to return to normal position under the action of its spring 87 to open the contact 91. Energization of the solenoid coil 105 will reverse the valve 109 and cause fluid under pressure to be directed through the pipe 112, thus to raise the piston rod 47 and disengage the crimping tool 27 from the rib 130 and, in this manner, the apparatus will be restored to normal condition, ready for another cycle of operation.

What is claimed is:

1. An apparatus for assembling an element having a thermoplastic adhesive on a surface thereof with a center portion and a rim portion of an article comprising a crimping tool for crimping the rim into clamping engagement with said element, means for actuating said crimping tool through one complete cycle of operation, a heating unit movable with respect to the crimping tool for engaging the element to render its adhesive plastic for adherence to the center portion, means for moving said heating unit into engagement with said element to heat it and press it onto the center position, and means controlled by said last-mentioned means for initiating operation of the crimping tool actuating means.

2. An apparatus for assembling an element having a thermoplastic adhesive on a surface thereof with a center portion and a rim portion of an article comprising a crimping tool for crimping the rim into clamping engagement with said element, fluid actuated means for moving said crimping tool through one complete cycle of operation, a heating unit movable with respect to the crimping tool, means for engaging said heating unit with said element to render its adhesive plastic and push it into adhering position on the center portion where it will be engaged by the rim portion during the crimping operation, and means controlled by said last-mentioned means for initiating operation of the fluid actuated means.

3. An apparatus for assembling an element having a thermoplastic adhesive on a surface thereof with a center portion and a rim portion of an article comprising a crimping tool for crimping the rim into clamping engagement with said element, means for actuating said crimping tool, a heating unit movable with respect to the crimping tool, means for engaging said heating unit with a surface of said element to render the adhesive on said element plastic and adherent and to transfer said element to engagement with the center portion and rim portion of the article, and a time delay circuit operable under control of said last-mentioned means to initiate operation of the crimping tool actuating means a predetermined length of time after the heating unit is moved.

4. An apparatus for assembling an element having a thermoplastic adhesive on the surface thereof with a center portion and a rim portion of an article comprising a crimping tool for crimping the ring into clamping engagement with said element, means for actuating said crimping tool, a heating unit movable with respect to the

crimping tool, means for engaging said heating unit with said element to heat it and move it into adhering engagement with the center portion and into engagement with a part of the rim portion of the article, and a time delay circuit operable under control of said last-mentioned means including a timer for delaying the operation of the crimping tool actuating means for a predetermined length of time after the heating unit engages said element.

5. An apparatus for assembling an element having a free surface and a surface having a thermoplastic adhesive thereon with a center portion and a rim portion of an article comprising a tubular crimping tool, a cylindrical heating unit slideable in said crimping tool, means for moving said heating unit into engagement with the free surface of the element to heat and plasticize the adhesive on the other surface thereof and press the element into adhering position on the center portion, and means operable under control of said moving means to move the crimping tool with respect to the heating unit to crimp a part of said rim into clamping engagement with said element.

6. An apparatus for assembling an element having a thermoplastic adhesive on a surface thereof with a center portion and a rim portion of an article comprising a hollow crimping tool for engaging a portion of said rim and crimping it over the edge of said element after the element is positioned on the center portion, a heating unit movable with respect to said crimping tool to engage said element to heat its thermoplastic adhesive to render it adherent and press it against the center portion in position to have the crimping tool crimp the rim over its edge, and means operable under control of the heating unit moving means to actuate the crimping tool.

7. An apparatus for assembling an element having a thermoplastic adhesive on the surface thereof with a center portion and a rim portion of an article comprising a hollow crimping tool, a heating unit slidably mounted in said crimping tool, manually operable means for moving said heating unit with respect to the crimping tool to engage the heating unit with said element for heating the adhesive to make it sticky and transferring the element into engagement with the center portion and the rim portion, a control circuit, means on said manually operable means for initiating operation of the control circuit, and means in said control circuit operable to initiate movement of said crimping tool with respect to said heating unit.

8. An apparatus for assembling an element having a thermoplastic adhesive on a surface thereof with a center portion and a rim portion of an article comprising a hollow crimping tool, a heating unit slidably mounted in said crimping tool, manually operable means for moving said heating unit with respect to the crimping tool to engage said element and heat it to make it adherent and transfer it into engagement with both the center portion and the rim portion, a control circuit, means on said manually operable means

for initiating operation of the control circuit, means in said control circuit operable to initiate movement of said crimping tool with respect to said heating unit to cause it to crimp a part of the rim portion over the edge of said element, means for latching said manually operable means in operated position, and means in said circuit for releasing said latching means.

9. An apparatus for assembling an element having a thermoplastic adhesive on a surface thereof with a center portion and a rim portion of an article comprising a crimping tool for crimping a part of said rim over the edge of said element, a heating unit mounted for movement with respect to said crimping tool, means for moving said heating unit to engage said element to heat it and make it adherent and transfer it into engagement with said center portion, a control switch operable by said moving means, means for actuating said crimping tool, and a switch in series with said control switch and normally held closed by said crimping tool actuating means.

10. In an apparatus for assembling an element having a thermoplastic adhesive on a surface thereof with a center portion and a rim portion of an article, the combination of a crimping tool for crimping an edge of the rim over an edge of the element and a heating unit movable with respect to the crimping tool to engage and heat the element to render its adhesive surface plastic and adherent and transfer the element into engagement with the rim portion and center portion, of a control circuit for said heating unit and crimping tools comprising a control switch operable upon movement of the heating unit, a switch normally held closed by the crimping tool, and a restoring switch positioned to be closed by the crimping tool at one extreme of the crimping tool's movement.

11. In an apparatus for assembling an element having a thermoplastic adhesive on a surface thereof with a center portion and a rim portion of an article, the combination of a crimping tool for crimping a part of said rim portion over an edge of the element, means for moving the crimping tool, a heating unit engageable with the element to position it with respect to the center portion and rim and to heat it to render its adhesive surface plastic and adherent, and means for moving the heating unit with a control circuit including a control switch, means interconnecting the means for moving the heating unit and the control switch for closing the control switch when the heating unit is moved, a timer operable upon closure of the control switch, a switch in series with the control switch and normally held closed by the means for moving the crimping tool, a switch positioned to be closed by the crimping tool moving means, means normally tending to restore the means for moving the heating unit to normal unoperated position, and a solenoid operable upon closure of said last-mentioned switch to render said last-mentioned means operable.

GEORGE STUHLFAUTH.
